UNITED STATES PATENT OFFICE.

JOHN F. HAMMOND, OF BREWSTER, NEW YORK.

SUSPENDED ELECTRIC DENTAL MOTOR.

No. 820,781.

Specification of Letters Patent.

Patented May 15, 1906.

Application filed April 27, 1905. Serial No. 267,597.

To all whom it may concern:

Be it known that I, JOHN F. HAMMOND, a citizen of the United States, residing at Brewster, in the county of Putnam and State of New York, have invented certain new and useful Improvements in Suspended Electrical Dental Motors, of which the following is a specification.

This invention has reference to the motors used by dentists for operating upon the teeth of a patient reclining in a suitable chair and for which purpose the motor is suspended, whereby it can swing horizontally and can, further, be raised or lowered in the various positions through which swung.

One of the objects of the invention is to provide an improved means for counterbalancing a motor, and especially an electric motor, in such adjusted positions.

A further object of the invention is to provide, in such a device, means for counterbalancing the motor in its normal position and means coöperating with said balancing means to properly balance the motor when moved above or below said normal position.

A further object of the invention is to provide means for suitably suspending the motor whereby it can rock on its axis of suspension and means whereby the motor can be removed from such suspension when swung to a position transverse to its normal position.

A further object of the invention is to provide an improved form of means for conveying the current to such a form of suspended member.

A further object of the invention is to provide, in a suspended dental motor operating a flexible shaft, means for readily connecting and disconnecting the flexible shaft with the motor.

Another object of the invention is to provide, in an electric suspended dental motor operating a flexible shaft, means for insulating the flexible shaft from the motor, thereby preventing any possibility of current from the same passing through the person operated upon.

In the drawings accompanying and forming part of this specification are shown embodiments of the present invention, wherein—

Figure 1 is a side elevation. Fig. 2 is a vertical middle section of the motor and suspended means. Figs. 3, 4, and 5 are detail views of the means for conveying current from the yoke to the motor. Fig. 6 is a

broken vertical section of the supporting means and the counterbalancing means carried thereby. Fig. 7 is an enlarged sectional broken view of the springs and other coöperating members shown in Fig. 6. Fig. 8 is a vertical section through a portion of the motor and supporting-yoke. Fig. 9 is a fragmentary side view of the motor-frame shown in Fig. 8. Fig. 10 is a transverse section on the line *x-x* shown in Fig. 1. Fig. 11 is a transverse section through the member by which the yoke and motor are flexibly suspended from the arm. Fig. 12 is a longitudinal sectional view through a connection of the flexible shaft with the shaft of the motor, and Fig. 13 shows the motor being removed from the yoke.

The present embodiment of the invention, as shown in Fig. 1, comprises a suitable arm 15, that is suitably supported at one end to swing in a vertical plane, and from its upper or free end is suspended a suitable motor 16 by means of a member 17 having a pivotal connection with the end of the arm. In connection with these three members—the arm, the motor, and the suspending member—is provided a supporting member attached to the arm and connected with suitable counterbalancing means, whereby when the arm 85 is moved from the horizontal position in which it is illustrated to the inclined position *a*, (indicated in broken lines,) wherein it will be observed the draft of the motor suspension on the arm is decreased by reason of the distance between the vertical line of suspension of the motor and the pivotal point of the arm being lessened, such counterbalancing means will compensate for this change of position and will properly balance the motor, 95 and not only will it counterbalance the motor in the two said positions, but in all positions therebetween.

One means of conveniently supporting the arm 15 to swing in a vertical plane and at the same time also swing in a horizontal plane in any of its positions in such vertical plane comprises an upright 18, supported to rotate on a vertical axis by means of two brackets 191 19, that may include a ball-bearing 20 to reduce friction. The upright member comprises a head 21, carrying a suitable vertical pulley 22 and having a neck 23, which has a pin connection with the upright tube 18. This upright tube passes through a suitable aperture in the lower bracket 191, fitting loosely therein, and has a ball-bearing be-

tween the bracket and a collar 25, secured on the tube.

Just below the bracket 191 a hinged member 26 is secured to the tube and has two apertured arms 27, between which the arm 15 is pivotally mounted on a vertical axis. The arm 15 is supported by means of a flexible cable 28, secured to the arm, preferably, at its outer extremity, and thence passing upward and around a guide-pulley 22, from which it passes downward through the upright 18 and brackets supporting it. The lower end of the cable is connected with a suitable counterbalancing-weight 29. The motor 16, being supported by a suspending member 17, having a swinging connection with the end of the arm 15, but arranged to support the member at a fixed distance from said end in the several positions of the arm when the motor is moved upward to the position indicated in broken lines in Fig. 1, it will be seen that the arm will not be perpendicular to the upright, but inclined thereto, which will bring its motor-carrying end considerably nearer the vertical line passing through the hinge of the arm. By moving to this position the end of the arm will evidently be brought much nearer to the pulley 22, which will permit the weight to fall to about the position indicated in broken lines. This change of position evidently will exert a much less draft on the cable 28 to support and counterbalance the weight of the arm and motor, and hence such weight as would properly counterbalance the arm and motor in the horizontal position will now overbalance such draft on the cable and would tend to raise the arm or retain it in such position, and such effect would assert itself very shortly after the arm left the horizontal position and increase from the horizontal position as long as its upward movement decreased the distance between the extremity of the arm and the pulley. In order to overcome such tendency of the weight, a suitable spring is provided that will have the effect of partially supporting the weight and decreasing its draft on the cable as the arm and motor are swung upwardly. In Figs. 6 and 7 are shown one form of such means in which a coil-spring 30 has its upper end secured to the lower extremity of the head 21, the spring being secured thereto by a screwing motion. To the lower extremity of such spring is secured a collar 31, its threaded exterior engaging the convolutions of the spring. A cylinder-tube 32 is secured to the weight and extends upward into the upright tube 18, the cable 28 passing from the pulley through an aperture in the head 21 and thence through the tube 32 and secured inside of the weight by any suitable means, such as a series of clamp-nuts 33. A suitable abutment, such as a washer 34 of less diameter than the inner diameter of the coil-spring

30, is secured to the inner tube 32 above the collar 31. The collar is so arranged that the arm can swing from the horizontal position to a position indicated by the broken line *a* without engaging the collar; but upon the arm swinging upward the lowering of the weight will move the inner tube 32 downward, and the washer will engage the collar 31 and distend the spring 30. This will evidently counteract the draft of the weight on the cable and will serve to counterbalance the decreased draft on the cable by reason of the angular position assumed by the arm.

Should the motor be thrown up quickly and the weight dropped rapidly, thereby increasing its draft by reason of the momentum of the weight, it is desirable to provide a cushioning device to augment the effect of the distending spring and to act as a kind of safety-stop at such stage. One form of means for accomplishing such result is shown as comprising a coil-spring engaged by the collar 31. A tube 35 is threaded into the lower extremity of the upright tube 28 and locked in place by lock-nut 36; and the lower end of tube 35 is closed, but has a central opening in which slides the inner tube 32. A coil-spring 37 is placed loosely around the tube 32 at the bottom of such tube 35, and when the arm approaches its dotted-line position *b* the collar 31 will strike this spring 37 and pressing it will arrest the further downward movement of the weight and inner tube, and thereby arrest the cable and arm. By screwing the tube 35 up or down, the range of movement of the washer 31, and consequently of the arm and motor, is adjusted.

When the arm is moved downward from the position *a* to the position *c*, the weight will counterbalance the draft on the cable 28 by the arm and motor; but when moved downward from the position *c* to the horizontal position it will increase the draft on the cable. Hence suitable means must be supplied to augment the draft on the cable by the weight. A convenient means for increasing such draft is shown in Figs. 6 and 7 as comprising a coil-spring 38, loosely surrounding the inner tube 32 and engaging the washer 34 on the tube, but being free from the surrounding coil-spring 30. This spring is so proportioned that upon the arm moving downward from the position *c* the consequent elevation of the weight and inner tube will cause the spring 38 to be compressed between the washer 34 and the lower face of the neck on the head 21. This will evidently oppose the upward movement of the weight and increase the draft on the cable 28, which will evidently counterbalance the increased draft on the cable by the arm and motor.

The leads or conductor-wires for conveying the current to the electric motor 16 are conveniently arranged by supporting them on

the arm 15 or passing them therethrough by using a tubular arm. From the end of the arm the leads pass downward contiguous to the cable-support 17 for the motor 16. By 5 this arrangement it will be seen that the cable is practically neither distended nor compressed in the several positions of the arm and motor, it simply receiving a slight flexure adjacent to the swinging support of the 10 arm and also at the swinging connection at the support 17 with the extremity of the arm, which can easily be arranged by using a flexible cable at such places of flexure. The support 17 may be arranged as shown in section 15 in Fig. 11, at the center being a flexible supporting-cable, surrounded by four or more insulated flexible leads, where it is desired to use separate leads for the field and the armature, and the whole incased in a suitable covering 40. In Fig. 10 is shown the arrangement of four leads and the supporting-cable 28, where they engage the curved extremity 41 of the arm 15, the supporting-cable 28 being at the middle and the pairs of leads on 25 each side thereof, the curvature preventing the sharp flexure of such flexible members when the arm is swung and the angle of the flexible members with the arm is changed.

A convenient way for supporting the motor 16 is to provide a frame or yoke 42, to the 30 ends of which the frame of the motor is pivoted. To convey current to the motor, swinging on such pivots at the extremities of one arm of the yoke a pair of spring-arms 43 are secured and connected with two of the leads 38, but insulated from the frame and each other. These arms bear on a pair of pins 44, respectively, passing through insulated bushings 45, and press them against arc-shaped 35 contact-plates 46, carried by the frame of the motor, but insulated therefrom. From these contact-plates wires 47 lead to the electrical parts of the motor. By this construction the motor can swing a considerable distance on 40 the pivots yet the pins still be in contact with the plates 46 and convey current to the motor. Where it is desired to run two sets of 45 leads, such arrangement of brushes and contact-plates is duplicated on the other side of the motor, one set of brushes connecting with the field and the other set with the armature or one of each kind on each side, as 50 most convenient. A modification of such arrangement is shown in Figs. 8 and 9, in 55 which a pair of brushes 48 are carried by the motor-frame and engage with a pair of insulated contact-plates 49, similar to the contact-plates 46, but which are secured to the inner face of the extremity of the yoke, the 60 leads 38 being connected with the insulated plates by passing through the frame 42. This arrangement is duplicated on the other side of the motor, where separate armature and field leads are provided.

65 The motor 16 is suspended from the yoke

42 in such a manner that by withdrawing the journals a short distance and then swinging the motor from its normal position to a position transverse thereto or at right angles therewith the motor can be withdrawn from 70 the journals; but in its normal position it cannot be withdrawn from the journals, because it would at once engage the yoke 42. The yoke 42 at each end is provided with a screw 62, located in a threaded bore 63 in the 75 yoke. In the motor-frame at each side is a socket 64, into which projects the end of the screw 62. In its normal position a flange 66 on the screw 62 stands adjacent to the motor-frame. On each side of the motor-frame is a channel 65, that is vertical when the motor is in its normal position and extends from the bore 64 downward to the end of such straight side of the frame, the width of the channel being slightly larger than the diameter of the 80 bearing portion of the bolt 62. When it is desired to remove the motor, the screw-bolts 62 are screwed outward until the flange 66 engages the inner face of the end of the yoke, which will prevent further withdrawal of the 85 bolt. When in this position, the end portion of the screw will still have a supporting engagement with the walls of the bore 64, but it will be in alinement with the channel 65. The motor is now swung to a transverse position or through an arc of ninety degrees and thereupon is moved in the direction of the 90 channel 65, so that the ends of the bolts will slide through this channel, as indicated in Fig. 13, until the bolts have passed entirely 100 through the channel, which will free the motor from the bolts. The motor is returned to its position in the same manner and then the bolts screwed inwardly to their former position. By this arrangement it will be seen 105 that it is not necessary to remove any part or parts of the device in order to remove the motor from the yoke, but merely to screw out the bolts for the limit of their movement. This will obviate the danger of any parts becoming 110 mislaid or lost.

For the purpose of removably attaching the flexible cable generally used with suspended dental motors to the motor and driving shaft means are provided, such as shown 115 in Figs. 1 and 12, comprising, essentially, a skeleton frame or member 50, that is removably secured to the frame of the motor which carries the flexible shaft and which is also preferably suitably insulated, whereby it is 120 impossible for current from the motor to flow into the tool or instrument attached at the end of the flexible shaft and thereby reach the person operated upon. The skeleton member 50 has a threaded neck portion 51, 125 that screws onto a collar 52, projecting from the motor-frame. The driving-shaft 53 of the motor projects through the collar 52 and when the frame 50 is screwed onto the collar 52 will project into the neck 51. The end of 130

the driving-shaft is connected with an insulating-plug 54 by means of a threaded sleeve 55, and to the plug 54 is secured a threaded rod 56, extending into the skeleton frame 50. 5 A flexible shaft 57 is carried by a suitable enveloping tube 58, which is secured to an extension 59 of the skeleton frame 50, but insulated therefrom by means of the insulating-collar 60. The extremity of the flexible tube 10 carries a rod 61, having a threaded bore arranged to screw into the threaded rod 56 in the interior of the skeleton frame 50, whereby the flexible shaft is connected with the driving-shaft of the motor. When it is desired to disconnect the flexible shaft, the fingers can be passed into the skeleton frame 50 and unscrew the end portions 56 and 61 of the motor-shaft and flexible shaft, respectively, and thereupon the flexible shaft, with 15 its enveloping tube, is unscrewed from the skeleton frame 50 of the motor-frame, thereby readily removing the flexible shaft from the motor. It will be observed that current is effectually prevented from passing through 20 the motor-frame and skeleton member to the flexible tube and casing by reason of the interposed insulating-sleeve 60 and also that the current is prevented from reaching the flexible shaft itself because of the insulating- 25 plug 54 separating the extremity of the driving-shaft from the connecting-rod 56.

The tube 32 has a slot 321 and is externally threaded to carry three nuts 322. The end of the cable 28 is passed out of the slot 35 below the upper nut, thence bent around the intermediate nut, and then returned through the slot into the tube and down and out at the lower end. Then the middle nut is screwed up to clamp the cable against the 40 upper nut, and thereupon the lower nut is screwed up to jam the cable against the middle nut, securely clamping the cable in such position. This permits the ready adjustment, of the cable.

45 Having thus described my invention, I claim—

1. The combination of an electric translating device an arm supported to swing in a vertical plane, a member having a swinging 50 connection with the arm and carrying said device, means for counterbalancing the arm and electric device in their several positions, and leads connected with the translating device.

55 2. The combination of an electric translating device, a member by which such device is suspended, means for supporting said member whereby it and the translating device can be raised and lowered, a balancing-weight 60 connected with the supporting means, and springs arranged to coöperate with the counterbalancing member whereby the translating device and supporting means are counterbalanced in a number of positions.

65 3. The combination of a member support-

ed to swing in a vertical plane, an electric translating device, a member pivotally suspended from the arm and carrying the translating device, and counterbalancing means connected with the swinging member and arranged to counterbalance the weight of the translating device and said members when the swinging member is swung through a predetermined path. 70

4. The combination of a suspending-arm 75 supported to swing in a vertical plane, an electric translating device, a member pivotally suspended from the arm and carrying the translating device, counterbalancing means connected with the arm and arranged 80 to counterbalance the weight of the arm-suspending member and translating device in the several positions of the arm.

5. The combination of means for supporting the arm at one end to swing in a vertical 85 plane, an electric translating device, a suspending member pivotally carried by the arm and secured to the translating device, a counterbalancing-weight connected with the arm and arranged to partially counterbalance the 90 weight of the arm and translating device, a spring coacting with said weight to increase its draft on the arm when the arm is swung to decrease the horizontal distance between the vertical line of the motor and the pivotal 95 point of the arm, and a spring arranged to counteract the draft of the weight on the arm upon the arm being swung to increase the distance between the vertical line of the motor and the pivotal support of the arm. 100

6. The combination of an arm supported to swing in a vertical plane, a suspending member pivotally carried by the arm, an electric translating device suspended by means of such member from the free end of the arm, 105 a counterbalancing member connected by a flexible member with the free end of the arm and suspended adjacent to the pivoted end of the arm, and arranged to counterbalance the arm and translating device in the several 110 positions of the arm.

7. The combination of an arm, means for supporting the arm at one end to swing in a vertical plane, an electric translating device, a suspending member pivotally connected 115 with the arm and carrying the translating device, a guide member arranged before the swinging support of the arm, a flexible member secured to the arm beyond its swinging support and passing around the guide member, 120 and a balancing-weight secured to the flexible member and arranged to counterbalance the arm and translating device.

8. The combination of an arm, means for supporting the arm at one end to swing in a 125 vertical plane, an electric translating device, a suspending member pivotally connected with the arm and carrying the translating device, a guide member arranged above the swinging support of the arm, a flexible mem- 130

ber secured to the arm beyond its swinging support and passing around the guide member, a balancing-weight secured to the flexible member and arranged to counterbalance the arm and translating device when in one position, a spring coacting with said weight to increase its draft on the flexible member when the arm is moved in one direction from said position, and a spring arranged to counteract the draft of the weight on the flexible member when the arm is swung in the opposite direction from such position.

9. The combination of an upright member supported to rotate on a vertical axis, an arm pivoted at the lower part of the upright to swing in a vertical plane, an electric translating device, a member supporting such device and having a swinging connection with the free end of the arm, a pulley mounted on the upright above the arm, a cable attached to the arm and passing around the pulley, a balancing-weight secured to the cable depending from the pulley and arranged to balance the arm and translating device.

15 10. The combination of an upright member supported to rotate on a vertical axis, an arm pivoted at the lower part of the upright to swing in a vertical plane, an electric translating device, a member supporting such device and having a swinging connection with the free end of the arm, a pulley mounted on the upright above the arm, a cable attached to the arm and passing around the pulley, a balancing-weight secured to the cable depending from the pulley and arranged to balance the arm and translating device in one position, a spring having one end connected with the upright, a detent connected with the weight and arranged to engage and distend the spring when the weight is lowered by raising the arm from said balanced position.

25 11. The combination of an upright member supported to rotate on a vertical axis, an arm pivoted at the lower part of the upright to swing in a vertical plane, an electric translating device, a member supporting such device and having a swinging connection with the arm, a pulley mounted on the upright above the arm, a cable attached to the arm and passing around the pulley, a balancing-weight secured to the end of the cable depending from the pulley and arranged to balance the arm and translating device in one position, and a spring arranged to be compressed when the weight is moved upward by the arm being lowered from said balanced position.

35 12. The combination of an upright member supported to rotate on a vertical axis, an arm pivoted at the lower part of the upright to swing in a vertical plane, an electric translating device, a member supporting such device and having a swinging connection with the arm, a pulley mounted on the upright

40 above the arm, a cable attached to the arm and passing around the pulley, a balancing-weight secured to the end of the cable depending from the pulley and arranged to balance the arm and translating device in one position, a spring having one end connected with the upright, a detent connected with the weight and arranged to engage and distend the spring when the weight is lowered by raising the arm from said balanced position, 70 and a spring arranged to engage the detent and be compressed when the weight is moved upward by the arm being lowered from said balanced position.

45 13. In a dynamo-electric device, the combination of a pair of supports, means whereby the device is pivotally suspended between said supports, the suspending means being arranged whereby the device is removable only when swung to a position transverse to 85 its normal position.

50 14. The combination of a yoke, a dynamo-electric device, means for pivotally supporting the device between the ends of the yoke, a part of each of such pivotal means being arranged to be withdrawn for a limited distance, and means for thereupon permitting removal of the device from yoke upon the device being swung to a position transverse to 90 its normal position.

55 15. The combination of a yoke, a dynamo-electric device, a journal carried by each end of the yoke, bearings carried by the device and engaged by said journals, the journals being arranged to be recessed in the bearings 100 for a limited extent, the device having a channel on each side disposed at right angles with said bearings and leading therefrom and extending vertical when the device is in its normal position, the channels being arranged 105 to permit the ends of the journals when recessed to such limited positions and the device swung to a position with the channels substantially horizontal to permit withdrawal of the device from the yoke by movement of the journals through the channels.

60 16. The combination of a dynamo-electric device, a yoke on which the device is pivoted, brushes carried by one of said members, and insulated contact-plates carried by the other 115 member and arranged to connect with the plates respectively when the device is swung on its pivotal connection with the yoke.

65 17. The combination of a dynamo-electric device, a yoke on which the device is pivoted, 120 a pair of brushes carried by each end of the yoke members, and a pair of insulated contact-plates carried by the device at each side and arranged to connect with the plates respectively when the device is swung on its 125 pivotal connection with the yoke.

70 18. The combination with a motor having a frame and a shaft, of a flexible shaft, a member surrounding the flexible shaft, a skeleton support secured to the surrounding 130

member and closing the extremity of the flexible shaft, the skeleton support being removably attached to the frame of the motor, the motor-shaft having its extremity extending into the skeleton member and removably secured to the extremity of the flexible shaft.

19. The combination with a motor having a frame and a shaft, of a flexible shaft, a member surrounding the flexible shaft, a skeleton support secured to the surrounding member and enveloping the extremity of the flexible shaft, the skeleton support being removably attached to the frame of the motor, the motor-shaft having its extremity extending into the skeleton member and secured to the extremity of the flexible shaft, a member arranged to insulate the skeleton member from the member surrounding the flexible shaft, and a member arranged to insulate the motor-shaft from the flexible shaft.

20. The combination with a motor having a frame and a shaft, of a threaded bushing projecting from the motor-frame, a skeleton member having a threaded sleeve arranged to screw into the threaded bushing of the frame, the shaft of the motor extending through said bushing into the skeleton member, a flexible supporting member secured to the skeleton member, a flexible shaft carried by the supporting member and having a screw-thread-

ed engagement with the end of the driven shaft extending into the skeleton member.

21. The combination with an electric motor having a frame and a shaft, of a threaded bushing projecting from the frame, a skeleton member having a threaded connection with said bushing, a flexible casing secured to the skeleton member, an insulating-bushing in said connection arranged to insulate the skeleton member from the casing, a flexible shaft carried by the casing and having a threaded extremity extending into the skeleton member, the shaft of the motor being located in said threaded bushing, an insulating-plug secured to the extremity of the latter shaft, and a threaded piece secured to the insulating-plug and projecting into the skeleton member and engaged by the threaded extremity of the flexible shaft.

22. The slotted threaded tube, three nuts on the tube and a cable in the tube passing out around the intermediate nut and clamped by the nuts.

Signed at Nos. 9 to 15 Murray street, New York, N. Y., this 24th day of April, 1905.

JOHN F. HAMMOND.
